UNITED STATES PATENT OFFICE.

WILLIAM A. EINIG, OF JACKSONVILLE, FLORIDA.

SPARKING PLUG.

968,333.

Specification of Letters Patent. Patented Aug. 23, 1910.

Application filed March 1, 1909. Serial No. 480,541.

To all whom it may concern:

Be it known that I, WILLIAM A. EINIG, a citizen of the United States, residing at Jacksonville, in the county of Duval and 5 State of Florida, have invented a new and useful Sparking Plug, of which the following is a specification.

This invention relates to sparking plugs used in internal combustion engines for igniting the charge in the engine cylinder, and 10 the object of the present invention is to provide an ignition device of this kind which is highly efficient in action, and devoid of complicated parts; and also to provide a 15 structure in which deposits of soot and other matter on the electrodes is effectually prevented, the electrodes being self-cleaning.

With the foregoing objects in view, the 20 invention consists in a novel construction and arrangement of parts for permitting the adjustment of the relative position of the electrodes and for guarding both from injury, as will be hereinafter described and 25 claimed, reference being had to the drawings hereto annexed in which—

Figure 1 is an elevation of the plug. Fig. 2 is a central longitudinal section. Fig. 3 is an end view.

In the drawings 5 denotes the conducting 30 casing which carries one electrode and is also constructed to support the other electrode. The casing is preferably a brass shell, and is open at both ends. Intermediate its ends, the shell is threaded externally as indicated at 6 and made angular near the threads as at 14 for attachment to the engine cylinder. That end of the conducting casing which extends into the engine cylinder is rounded off or dome shaped 35 and provided with diametrically opposite lugs 8 projecting beyond its body, and across the opening at this end, extends a fine platinum wire 7 which is in electrical connection with the casing and serves as one of the 40 electrodes of the plug. The wire is secured at its ends to and guarded from injury by the lugs 8, and bows outward between them as shown, so as to permit expansion and contraction without injury. The other electrode of the plug is a short section of wire 45 50 which is screwed into a metallic cap 10 at the end of a core 11 of insulating material such as mica. The core extends into the casing 5 from that end thereof which is on the outside of the cylinder, and adjacent 55 said end it has on the outside thereof a

shoulder 12 engaged by a cap nut 13 screwed on said end of the casing. Between the end of the casing and the shoulder 12 is placed a washer 15. Extending axially through the core 11 is a rod or wire 16 which screws at one end partly into the cap threaded bore through the cap 10, whereby said cap is held against the inner end of the core; and on the other end of the rod or wire is screwed a 60 nut 17 which clamps a clip 18 against the outer end of the core, said clip serving as a connection for the wire 19 with the plug. The electrode 9 is a short piece of non-corrosive wire known to the trade as "meteor" 65 wire, and it screws into the outer end of the threaded bore in the cap 10. The outer end of this wire stands between and is guarded by said lugs 8 and extends into close proximity to the wire 7, where the latter is 70 bowed slightly in a direction away from the former.

The electric current passes along the rod or wire 16 from the clip 18 and wire 19 and into the cap, and from the cap 10 to the electrode 9. It then jumps or sparks across the gap between said electrode and the electrode 7 and passes through the casing 5 to the engine cylinder in the usual manner.

Normally the parts will stand about as shown in Fig. 2; but it is obvious that the meteor wire electrode can be adjusted longitudinally by screwing it into or out of the threaded bore in the cap 10, and when adjusted, the rod 16 can be screwed farther into said cap until it bears on the upper end of the electrode 9 and thus serves as would a jam nut to prevent the electrode from becoming loose in the cap, and when the nut 17 is again tightened the rod will be held against movement through the core 11. Ordinarily adjustment of the electrode nearer the platinum from time to time is effected by forcing the core farther into the casing, and that adjustment is also possible with the present construction because the washer 15 might be compressed or replaced by a thinner one; hence my improved construction of parts provides for two adjustments, and either or both may be employed.

A sparking plug constructed as herein described can be cheaply manufactured, and the parts can be readily assembled. There are no complicated parts to get out of order, and the plug will therefore be efficient and reliable in action. The exploding charges heat the platinum wire 7 to a red heat which

burns off all grease and carbon deposits at every explosion, thereby keeping the electrode absolutely clean and preventing deposits of soot thereon.

5 What is claimed is:

A spark plug comprising a tubular conducting casing having a dome-shaped inner end and diametrically opposite lugs projecting therefrom, a platinum electrode connected at its extremities to said lugs, an insulating core within the casing, an axial rod through the core and having threaded projecting ends, a nut and circuit wire engaging its outer end, a conducting cap against 10 the inner end of the core and having a threaded bore completely through it partly engaged by the inner end of said rod, and a

second electrode having its outer end extending between said lugs into proximity with the platinum electrode and its inner end threaded and adjustably engaging the bore of said cap, whereby after setting this electrode therein said rod can be screwed farther into the cap to jam upon the inner end of said electrode for the purpose set forth.

In testimony that I claim the foregoing as my own, I have hereto affixed my signature in the presence of two witnesses.

WILLIAM A. EINIG.
